UNITED STATES PATENT OFFICE.

RODOLPHE WILLIAM BURCKHARDT, OF MULHOUSE, FRANCE.

DEVICE FOR EFFECTING THE MIXING OF GASEOUS STRATA.

1,419,216.

Specification of Letters Patent. Patented June 13, 1922.

Application filed August 10, 1920. Serial No. 402,732.

To all whom it may concern:

Be it known that I, RODOLPHE WILLIAM BURCKHARDT, citizen of the Republic of Switzerland, residing at Mulhouse, Department of the Haut-Rhin, in France, and having post-office address 10 Rue Saint-Jean, in the said city, have invented certain new and useful Improvements in Devices for Effecting the Mixing of Gaseous Strata (for which I have filed an application in France, July 31st, 1919); and I do hereby declare the following to be a full, clear, and exact description of the invention, such as will enable others skilled in the art to which it appertains to make and use the same.

This invention consists in a device for effecting rapidly the mixing of gaseous strata flowing or circulating in flues or other passages. Its main object is to mix with combustible gases the air necessary for their combustion, but it may of course be applied wherever it is desired to mix any two gases circulating in one and the same passage.

As is well known, it is usually very difficult to mix combustible gases rapidly with non-combustible gases and the means generally employed heretofore, in connection with steam boilers in particular, do not give the desired result. The chief difficulty to be overcome is that different strata of gases, such as issue from a boiler furnace, persist in flowing parallel to each other and it is essential that the mixing be effected rapidly, i. e., while the gases are traversing as short a distance as possible. The present invention enables thorough mixing to be effected in a much shorter distance than heretofore.

My invention is illustrated in the accompanying drawing, in which:

Fig. 1 is a diagram which enables the essential feature of the invention to be readily understood;

Figs. 2, 7, 8 and 9, show different forms of the members constituting the device; and Figures 3, 4, 5 and 6 represent diagrammatically different arrangements of these members.

Assuming that the flue or passage is rectangular as shown in Fig. 1 and that a combustible gas into which the air necessary for combustion has been introduced is flowing upwards, the air will flow along with

the current in one or more columns or strata parallel to the combustible gaseous column or columns and the distance traveled would be very considerable before mixing would be effected.

Let it be assumed that the columns 1, 1¹, 1² represent the current of air, and that the columns 4, 4¹, 4² represent the gaseous combustible current, the columns 2 and 3 being assumed to be already mixed. The device which constitutes the subject matter of the present invention consists essentially in the employment of tubes of suitable shape which are mounted in the flue or passage at an angle to the axis of the said passage, substantially as indicated in Fig. 1, the said tubes being in contact with the opposite walls at their ends. In certain cases inverted gutters or semi-tubes, such as illustrated in Fig. 2, may be substituted for the aforesaid tubes.

It will be readily understood from Fig. 1 that the column 1¹ in rising will enter the tube 5 and will be conducted to the other side of the flue or passage, and that the columns 4, 4² will in the same way be caused to pass to the opposite side of the flue through the tubes 6 and 7; and it follows therefrom that if a number of these tubes are superposed, arranged in alternating crossed relation, a systematic transfer of the gases from one side of the passage to the other and an intimate mixing of the gases will thus be very rapidly effected. The mixing is completed by the deflection and mingling caused by the obstacles which these tubes constitute.

Substantially the same result may be obtained with the means illustrated in Fig. 2, although the action is somewhat less positive and, in consequence, the apparatus has to be extended a little further.

In practice the two means could be combined by employing complete tubes, as shown in Fig. 7, in the first stage, and then completing the mixing with inverted gutters as shown in Figure 8. The combination of tubes and semitubular gutters shown in Fig. 9 combines the advantages of both means.

In Figure 4 the tubes are superposed parallel to each other but extending obliquely across the flue so that the column or stratum which has escaped from the first row meets

the second row in its ascending movement, and so on.

The arrangement shown in Figure 3 is applicable chiefly to larger flues or passages, 5 for which it would be difficult to make of refractory materials sufficiently long tubes: in this case semi-tubes which conduct the deflected portions of the gaseous current from the walls toward the centre are employed.

10 In Figures 5 and 6 arrangements in which the tubes or semi-tubes are crossed are indicated.

It will be seen from the foregoing that by arranging and spacing apart a number 15 of tubes, semi-tubes or inverted gutters in the manner described the gaseous strata or columns are divided up into a number of veins or streams. Every second vein or stream can pass freely between the tubes or 20 semi-tubes which, on the other hand, deflect the other half of the divided current and oblige the portions passing therethrough to follow trajectories different from those of the veins or streams which pass between 25 them. The gases which pass through the inclined tubes or semi-tubes are thus transferred into other zones of the current where they come into contact with gases having different characteristics and with which it is 30 desired to mix them.

This systematic and mutual transfer, vein by vein, of the different strata or columns from one to the other may be repeated several times by providing several rows of these 35 inclined tubes or semi-tubes arranged one

after the other and preferably in crosswise formation.

Claims:

1. A mixing device for gases flowing or circulating in strata or columns parallel to each other, the combination of a flue, or the like, conducting said gases, and a series of substantially hollow obstructions extending obliquely across said flue, whereby the gases passing along one side of the flue are caused to pass into and cross over through said hollow obstructions and be conducted to the opposite side of said flue in a direction transversely to the general flow, resulting in a complete intermingling and mixing of said 45 gases.

2. A mixing device for gases flowing or circulating in strata or columns parallel to each other, the combination of a flue, or the like, conducting said gases, and a series of 50 diagonally disposed tubular members extending crosswise of each other within said flue, whereby the gases from the opposite sides of said flue are caused to cross over, passing into and through said tubular members and be conducted in a direction transversely to the general flow, resulting in a 55 complete intermingling and mixing of said gases.

In testimony whereof I affix my signature, 60 in presence of two witnesses.

ROD. WILLIAM BURCKHARDT.
